Lion Ribbon Co., New York, N. Y.

Application January 5, 1955, Serial No. 33,843

Term of patent 7 years

(Cl. D80—9)

To all whom it may concern:

Be it known that I, Harry Lewis, a citizen of the United States of America, residing at Valhalla, county of Westchester, and State of New York, have invented a new, original, and ornamental Design for a Counter Display Rack, of which the following is a specification, reference being had to the accompanying drawing, forming part thereof, wherein:

Figure 1 is a front perspective view of a counter display rack showing my new design.

Figure 2 is a rear perspective view of same, drawn to a smaller scale, and showing the upper member thereof in separated position.

Figure 3 is a top elevational view of the counter display rack shown in Figure 1, drawn to a smaller scale.

I claim:

The ornamental design for a counter display rack, substantially as shown and described.
